ELECTRIC HEATING ELEMENT

Marcel Marie Joseph Eugène Coupier, Paris,
FranceApplication July 9, 1935, Serial No. 30,578,
In France July 19, 1934

3 Claims. (Cl. 201—67)

It is well known that electric heating elements may comprise a resistant helically wound wire embedded in mineral insulating material such as magnesia, the whole being enclosed in an outer metal sheath.

The mineral insulation may be introduced as a powder inside a metallic tube containing a helically wound resistance, after which said tube is closed at its ends and is submitted to an outer compression through tensioning or restriction of area, so as to provide a good thermic contact and sufficient compactness.

On the other hand the insulating material, constituted say by magnesia, may be formed in situ starting from magnesium in which case the coiled resistance is held in place by reason of the swelling of the magnesia when forming.

The first method mentioned does not allow a perfect contact to be obtained as the possible compression may be limited by the fact that when it is attempted to increase it, there is a risk of breaking the coiled resistance. The second method which provides a better contact shows the drawback that it forms a limitation to the choice of the insulating material, and furthermore that it requires a passage through the metallic stage, whereas it may be of interest to use directly pulverized mineral material which may be set in place either directly or as compressed tablets of insulating material to be crushed through compression once in place.

My invention has for its object a method for making electric heating elements providing the advantages of the first above-described method without showing its drawbacks. It consists in using when compressing the pulverized insulating material, a solid core holding inwardly the resistance coil so as to avoid the crushing of the latter and to provide a more considerable compression of the insulation than with the methods used heretofore.

The insulation may be simply in the pulverized state, or form tablets of compressed powder.

As to the solid core, it may be of insulating or conducting material. Thus it may be of a pulverized compressed material similar to or different from the pulverized insulating material, of material softening when hot, or fusible or friable or of any desired metal.

According to its nature or according to the deformations to be imparted to the heating resistant element after compression of the insulating material, the core may be left in place after said compression or be removed.

Different possible forms of execution are de-

scribed hereinafter by way of example, without this description being in any manner limitative.

In the case of rectilinear elements, I may use a sufficiently hard metallic core constituting a mandrel which is removed after compression of the insulating material, which removal may be furthered by a conical shape given to the mandrel or by a helical groove thereon which allows the removal of the mandrel through rotation, said helical groove being associated if required with a conical shape of the mandrel.

In the same case of rectilinear elements, I may also use a central core, threaded or not, of insulating material, moulded or machined and capable of retaining its electric properties at the temperature of use. It is sufficient for the material of the core to show at the start a resistance to deformation such that it may resist the final compression to which the insulation embedding the resistant coil is to be submitted. I may use for instance small rods of compressed steatite or special porcelain or even metallic cores enclosed in sheaths of mica or the like hard insulating material. In the case of a core formed of a central metal part enclosed in an insulating sheath of insulating material such as compressed powder, the central metal part or core may be removed or not after compression.

When the resistances are to be folded after they have been embedded in compressed insulating material, I may use for the inner core insulating material capable of being folded when hot or cold without any damage to the resistant wire. Thus for instance the core may be constituted, in the part to be bent alone or throughout, by a mandrel capable of deformation when hot or cold adapted to be removed or left in place according as to whether it is electrically conductive or becomes so for instance when hot or is not conductive.

I may for instance use a mandrel of insulating material such as agglomerated mica and glass which softens when very hot and thus allows the bending of the hot core, while holding the resistant winding which remains properly centered inside its sheath of compact powder.

I may also in certain cases use a metal or alloy which melts sufficiently underneath the melting point of the resistance and of its sheath for preventing any alloying therewith and allowing it to flow out so as to leave the central part of the finished resistance free after compression, I may in particular use to this end, aluminium alloys which allow an oxidation of any traces of metal remaining after melting so as to transform them into insulating particles. It

is, of course, also permissible to use any other metal or other suitable material which is fusible enough to allow its being removed through melting before or after the shaping of the resistant element.

One embodiment of my invention is shown, solely by way of example, in the attendant drawing, wherein the single view is a longitudinal, broken section through an assembly according 10 to my invention.

By way of example the single figure shows a device according to the invention before it is submitted to outer compression. The device comprises a cylindrical mandrel 1 of aluminium 15 or an alloy thereof or of other convenient material. On said mandrel is wound a conducting wire 2 constituting the heating resistance; the mandrel and wire are disposed inside a metallic sheathing 3 and the hollow space remaining between the mandrel and sheathing is filled with 20 mineral powdered material, say with magnesia. The sheathing is closed at both ends by convenient plugs to prevent the magnesia from falling out; the assembly thus prepared is then submitted to a pressure (rolling or drawing). After 25 said operation the assembly may eventually be bent hot or cold, and then submitted to a temperature such that the mandrel melts and flows out without damaging the wire.

30 The core may also be constituted by insulating material of the same nature as or of a nature different from the insulating material surrounding the conducting coil. This core, being thus made of compressed powder will, when the 35 resistant element is deformed, be reduced into powder without any modification in volume. It continues therefore filling without any lack of continuity the inside of the element. The core may in particular be constituted by small cylindrical rods of very greatly compressed magnesia.

40 This core may as stated hereinabove, be compound and comprise an inner part of metal enclosed inside a system of cylindrical rods of compressed insulating material which maintains the 45 insulation between the winding and the core during bending when the metal has not been previously removed.

45 The heating element may be made by winding the winding over the core or else by engaging the core inside the winding and causing the coils 50 to bear against the core through a traction exerted on the ends of the winding while it is engaged inside the outer sheath and the insulation is compressed round it.

55 When the outer insulating material is formed of compressed tablets or blocks, I prefer giving the core a rate of compression which is higher than that of the compression exerted on the outer insulating material.

60 The core may also be constituted by a highly tempered glass rod. Such a core is sufficiently resistant to allow a tight winding round

it of the resistant wire and will resist the compression without breaking but it will crumble into fine granular particles, which cannot damage the wire, when the final shape is being given to the resistant element.

5 I may of course introduce insulating powder in any suitable manner round the winding and in fact in the case of magnesia insulation prepared in situ I may compress it after formation over a removable or stationary core so as to improve its compactness.

10 In the case where the core, set in place during compression, is subsequently removed, it is possible to submit the element constituted by the external tube or sheath, the compressed mineral insulation and the winding inside which a vacant space remains, to any of the usual treatments rendering the insulating material less hygroscopic or more compact such as for instance an impregnation with boric acid.

15 I have only mentioned hereinabove the application of my invention to heating elements; but obviously it applies also and still better to conducting windings and solenoids for which the setting in place and winding over a core are rendered more easy by the larger size of the coils.

20 What I claim is:

25 1. A method for making an electric resistance which comprises winding a conductor as a helix over a core of aluminium, embedding said core and conductors in a mineral insulation material, enclosing said embedded core and conductor within a metal sheath, subjecting said sheath and its content to the action of pressure, bending the whole to a desired shape and then submitting it to the action of a temperature above the melting point of the core, whereby the melted core runs out of the sheath.

30 2. A method for making a substantially cylindrical electric resistance which comprises winding a conductor as a helix over a core of aluminium, embedding said core and conductor in a mineral insulation material, enclosing said embedded core and conductor within a metal sheath, subjecting said sheath and its contents to the action of pressure, and then submitting 35 it to the action of a temperature above the melting point of the core, whereby the melted core runs out of the sheath.

35 3. A method for making a curved electric resistance which comprises winding a conductor as a helix over a core of aluminium, embedding said core and conductor in a mineral insulation material, enclosing said embedded core and conductor within a metal sheath, subjecting said sheath and its contents to the action of pressure, bending the sheath and its contents to the desired shape, heating said sheath and contents sufficiently to melt the aluminium core, and allowing said melted core to run off.
